UNITED STATES PATENT OFFICE.

WALTER S. PINION, OF PHILADELPHIA, PENNSYLVANIA.

SUBMARINE.

1,317,033.

Specification of Letters Patent. Patented Sept. 23, 1919.

Application filed September 13, 1918. Serial No. 253,977.

To all whom it may concern:

Be it known that I, WALTER S. PINION, a citizen of the United States, residing at 723 S. 19th street, Philadelphia, in the county of 5 Philadelphia and State of Pennsylvania, have invented new and useful Improvements in Submarines, of which the following is a specification.

This invention relates to submersibles in 10 general, and more particularly to a submarine adapted for ramming a vessel or other floating body, whereby the destruction of said vessel or floating body may be effected.

The main object of my invention is to provide 15 a simple and effective means whereby the angular inclination for the submerging or raising of a submarine may be effectively controlled.

A further object of my invention is to 20 provide a submarine with an efficient means for ramming and piercing the hull of a vessel or other body when so desired, together with a means for withdrawing the submarine or forcing the same away from the hull 25 of the vessel or other body so rammed.

A still further object of my invention is to provide a novel means whereby the port-hole lights or other aperture-covering portions may be automatically controlled.

With these and other objects in view, as 30 will later on be more clearly apparent, my invention consists essentially in the novel features of construction, combination and arrangement of parts, hereinafter more fully 35 described and particularly pointed out by the appended claim.

In the further disclosure of the invention, reference is to be had to the accompanying drawings, constituting a part of this specification, in which similar characters of reference denote corresponding parts in all the views, in which—

Figure 1 is a port-side view of a submarine partly broken away or in section, showing 45 the improved incline controlling mechanism, as well as the ramming device.

Fig. 2 is a plan view of the same similarly broken away or in section to show the underlying parts, as well as more fully showing 50 the means for projecting the submarine away from a vessel or other body when rammed.

Fig. 3 is a fragmentary plan view of the means for forcing the submarine away from 55 the hull of a vessel or other body when rammed, in its operative position.

Fig. 4 is a perspective view of one of the incline controlling blades or fins.

Fig. 5 is a cross section of the ram.

Fig. 6 is a diagrammatic view of the wheel 60 for controlling the inclining mechanism.

In the drawings, the numeral 10 indicates the hull or body of a submarine, and according to my improvements there is provided transversely of the fore part thereof a horizontal shaft 11, mounted in appropriate bearings, and carrying a worm wheel 12 in mesh with a worm 13 on a fore and aft shaft 14 under the control of a hand wheel 15. Suitably connected to the outer ends of the 70 aforesaid shaft 11 are connecting rods 16, in turn pivotally connected to rods 17 pivoted to the incline controlling blades or fins 18. These blades or fins 18 are normally horizontally disposed, and they are pivotally mounted on stub axles 19 projecting from the sides of the submarine's skin, and they are also furnished at their forward ends with laterally projecting pintles 18', engaging in arcuate guides 20. The pintles 18' have heads 19a 80 which engage between the guides 20 and the exterior of the hull so as to keep the movement of the blades or fins 18 in paths parallel with the guides 20 and thereby prevent any lateral turning movement of the hull 85 from moving the blades or fins away therefrom. Thus the straining of the connecting parts is prevented, and it will be seen that when the hand wheel 15 is rotated in one direction, for instance, to the right, the 90 blades 18 will be downwardly inclined, and the nose of the submarine will be deflected downwardly. A reverse rotation of the hand wheel 15 will effect an upward inclination of the nose of the submarine. 95

Forwardly of the submarine I provide a projecting ram 21 which is preferably made of the cross section shown in Fig. 5, that is to say, somewhat star-shaped, so that when it pierces the hull or skin of a vessel, it will 100 effect a tearing action. In order to provide a ready withdrawal of the ram, I furnish the submarine with the means shown more fully in Figs. 2 and 3, and which briefly consists of an operating rod 22 secured to a laterally movable guide 23 which has pivoted to its outer ends links or rods 24, in turn pivoted to links or rods 25, the free ends whereof are pivoted to a common or fixed center 26. Short links or rods 27 are pivoted to the aforesaid links or rods 25 and also to links or rods 28, which are provided

at their outer ends with buffer devices 29, and said links or rods 28 are also pivoted to fixed center or centers 30. The operation of this mechanism will be clearly understood 5 from Figs. 2 and 3, the former of which shows the inoperative position, and the latter the operative position.

In order to provide a simple and effective means for operating the aforesaid mechanism, I connect the operating rod 22, with 10 the piston of a cylinder 31 communicating with a supply of compressed air or other motive fluid through connections 32, so that when said compressed air acts on the rear 15 side of the piston the device is moved into its operative position, as shown in Fig. 3, and reversely, when the compressed air acts on the forward end of the piston, the device is moved to the inoperative position shown 20 in Fig. 2.

In Fig. 6 the operating wheel 15 is shown to an enlarged scale, and it is provided with a pointer 33 adapted to move over a graduated scale 34, which is provided to indicate 25 the angular inclination of the blades 18 above referred to.

From the foregoing description it will be readily seen that I provide certain new and extremely useful features in connection with submersibles, and I wish it clearly understood that I do not limit myself to the precise details hereinbefore briefly outlined, but consider myself free to make such detail changes as will adapt my invention to different requirements, such changes and other 30 combinations of the several parts being, however, limited by the scope of the appended 35 claim.

I claim:

A submersible boat including a hull; deflecting fins; means pivotally connecting said deflecting fins to the hull; means for moving said fins on its pivotal connection; arcuate guides secured to the exterior of said hull; and headed pintles on said fins extending 40 through slots providing said arcuate guides, the heads of said pintles being of greater width than said slots and being positioned 45 between said guides and said hull; substantially as described. 50

In testimony whereof I affix my signature.
WALTER S. PINION.
